GEORGE W. WHITEMAN, OF PHILADELPHIA, AND CHARLES W. REINOEHL, OF STEELTON,
PENNSYLVANIA.

INSULATED SWITCH-BAR FOR RAILROADS.

932,208.

Specification of Letters Patent. Patented Aug. 24, 1909.

Application filed February 29, 1908. Serial No. 418,585.

To all whom it may concern:

Be it known that we, GEORGE W. WHITEMAN and CHARLES W. REINOEHL, citizens of the United States, said WHITEMAN residing in the city and county of Philadelphia, State of Pennsylvania, and said REINOEHL residing at Steelton, Dauphin county, State of Pennsylvania, have invented certain new and useful Improvements in Insulated Switch-Bars for Railroads, of which the following is a full, clear, and exact description, reference being had to the accompanying drawings, of which—

Figure 1 is a section across a railroad track, showing a switch bar embodying our invention and connected to the point-rails of a switch. Fig. 2 is a plan view of the portion of the switch bar in which our invention is embodied. Fig. 3 is a vertical medial section through the same.

The object of our invention is to provide a strong and efficient switch bar or connecting bar, one portion of the same being electrically insulated from the other portion.

To this end the invention consists in dividing the usual connecting bar or switch bar into two portions, overlapping each other in the nature of a splice, and whose opposed surfaces are separated by an intervening strip or plate of insulating material, the said overlapping ends being secured together by means insulated from one or both of the bars.

The precise nature of the invention will be hereinafter particularly pointed out.

1, 1, are the usual stock rails, and 2, 2, the point rails of a railroad switch; 3, the lugs secured to the point rails, and 4, the switch bar pivotally connected to said lugs in the well known manner.

The bar, 4, is divided into two sections, 4^a and 4^b whose adjacent ends overlap, as seen in Figs. 1 and 3; and their opposed surfaces consist of complementary undulations, said surfaces being separated from each other by an intervening strip or plate, 5, of insulating material. Each section 4^a and 4^b of the bar 4 is bent near the meeting ends of the sections, as shown, to offset the overlapping ends from the longitudinal centers

50 of the sections, thus bringing the main body portions of the two sections into alinement with each other. The overlapping ends are secured together by means of bolts, 6, which, with their nuts, 7, are each insulated from

one portion of the bar, 4, by an insulating washer, 8.

We remark that, by the construction shown and described, not only is the thickness of the switch bar rod at the joint between its parts reduced to a minimum; but, by reason of the undulating or curved surfaces of the connected parts, much greater longitudinal strength is attained than would be the case were the overlapping ends of the bars a plane surface.

Having thus described our invention, we claim as new and desire to secure by Letters Patent:—

1. A connecting bar or rod for railroad switches and the like, comprising two sections whose adjacent ends are provided with overlapping undulating opposite surfaces, one of said sections being bent to offset the overlapping portion thereof from the longitudinal center of the section, the insulating material between said surfaces, together with means insulated from one of said parts securing said overlapping ends together, substantially as set forth. 70

2. A connecting bar or rod for railroad switches and the like, comprising two sections whose adjacent ends are provided with overlapping undulating opposite surfaces, one of said sections being bent to offset the overlapping portion thereof from the longitudinal center of the section, the insulating material between said surfaces, together with the bolts securing said parts together, said bolts being respectively insulated from one of said parts, substantially as set forth. 90

3. A connecting bar or rod for railroad switches and the like, comprising two sections whose adjacent ends overlap each other, one of said sections being bent to offset the overlapping portion thereof from the longitudinal center of the section insulating material between said overlapping ends, together with means insulated from one of said parts securing said overlapping ends together, substantially as set forth. 100

In testimony whereof, we have hereunto affixed our signatures.

GEORGE W. WHITEMAN.
CHARLES W. REINOEHL.
